UNITED STATES PATENT OFFICE.

JOHN EDWARD ROBINSON, OF BOSTON, MASSACHUSETTS.

IMPROVEMENT IN SAND AND AIR CHAMBER FOR TUBULAR WELLS.

Specification forming part of Letters Patent No. **103,239**, dated May 17, 1870.

I, JOHN EDWARD ROBINSON, of Boston, in the county of Suffolk and State of Massachusetts, have invented a Sand and Air Chamber for Tubular Wells, of which the following is a specification:

Nature and Object of the Invention.

The nature of my invention is that of a peculiar arrangement of pipes and a diaphragm, placed in a tube, by which I secure an air-chamber to regulate the working of the pump, and also separate sand and other heavy impurities from the water.

The figure shows a side view of the inner portion of my invention with a vertical section of the outer case.

General Description.

A A is a cylindrical tube, representing the barrel or outer case of my sand and air chamber.

The lower end of the chamber is hermetically closed by a cover or bottom plate, B, which is convex externally, and bears on one side of its center a male screw, C, with an external lip or flange, called the "trap-screw," fitting in a female screw borne by the cover. The object of this screw is, that on being removed the sand separated from the upflowing current of water, having subsided and settled on the bottom piece, C, may be withdrawn.

D is a metallic diaphragm in the shape of a cup, whose convex surface is uppermost, fluted radially, and extending entirely across the inner part of the chamber A A.

The radial fluting is not absolutely essential, but it is preferable.

This diaphragm D is borne by a tube, E, called the "lower tube," whose lower end passes through the lower cover or bottom, B, is fastened there, and projects beyond it an inch or more. The upper end of this lower tube passes through the diaphragm a little one side of its center, is firmly fastened there, and the top tube-opening opens on the upper side of the diaphragm.

F is the upper tube, and its lower end passes through to the lower side of the diaphragm, (opening there below,) a little one side of the center of the same, and is firmly fastened to it. The upper end of this upper tube, F, passes

through the upper cover, G, of the chamber, being fastened there, and projects an inch or more beyond the upper surface of this cover, there thus being a double support to the diaphragm D.

Operation.

To use this device of mine, I connect the upper tube, F, with the tube of a pump, and the lower tube, E, with the upper end of a tubular well.

Working the pump, the following action takes place: Both connections having been hermetically sealed, the air is withdrawn from the chamber. The water, &c., ascends in the lower tube, E, and, being discharged at the upper aperture of the same, runs down the radial flutings of the diaphragm, and falls into the lower division of the chamber.

The sand, &c., owing to its superior gravity, falls down onto the lower cover, B, whence it is at pleasure withdrawn by means of the trap-screw C.

The center of this body of water in the lower division of the chamber is free from sand, the force of the current not being sufficient to draw the sand up again, and it is at the center, or rather very near to it, that the lower end of the upper tube opens. Through this aperture the water, clear and free from impurities, passes up to the pump. Thus one function of my device is fulfilled.

The upper aperture of the lower tube, E, is slightly above the level of the lower aperture of the upper tube, F, and the surface of the water contained in the chamber is coincident with the top of the lower tube, thus leaving a space above the diaphragm filled with air, which air operates to regulate and equalize the flow of the respective ascending currents in the tubular well and in the pump, in the usual manner of air-chambers connected with pumps, which is the second object of my device.

And I do not confine myself to a radially-fluted diaphragm, nor to the pitch shown of its convex surface, nor to any specific dimensions as to width and length of my chamber; and I sometimes use two or more sets of pipes and diaphragm; and sometimes, instead of bending the pipes E and F away from the cen-

ter of the diaphragm, I fork either the upper or the lower pipe where it meets the diaphragm, letting the other pipe enter the diaphragm at the center.

I do not claim placing a filtering apparatus in the course of the upward current of a pump; but

I claim as my invention—

The closed chamber shown and described,

in combination with the tubes and the semi-globular or conical diaphragm, all constructed and arranged substantially as and for the purpose described.

JOHN EDWARD ROBINSON.
